WORK SUPPORT

Frank Bycroft Keall, Leicester, England, assignor to United Shoe Machinery Corporation, Paterson, N. J., a corporation of New Jersey

Application April 1, 1931, Serial No. 526,916,
and in Great Britain April 28, 1930

19 Claims. (Cl. 1—41)

This invention relates to work supports for fastening inserting machines and is illustrated herein as embodied in a machine of the type disclosed in Letters Patent of the United States, No. 5 1,904,313, granted April 18, 1933, on an application filed in the name of Charles Frederick Reginald Jeavons.

Heels which have metallic tips attached to their rear portions are often provided with top lifts which are cut out to receive the metal tips so that the upper surfaces of the metal tips will form part of the tread surfaces of the heels. These metal tips are provided with perforations through which the fastenings are inserted and 15 in order that the metal tips and the top lifts of the heels will form unbroken tread surfaces and also to prevent the metal tips from projecting beyond the edges of the heels it is necessary that the metal tips be held closely in contact with the 20 cut-out portions of the top lifts during the fastening inserting operation. It has been found in practice that small portions or burrs are frequently left on the edges of the metal tips of such a nature that considerable force or pressure is 25 required to position the metal tips closely in contact with the edges of the top lifts.

In view of the above, it is an object of the present invention to provide a work support for fastening inserting machines of such a character 30 as to facilitate the positioning of metal tips and unattached heels prior to the fastening inserting operation. With this object in view a feature of the invention resides in means whereby the machine operator may conveniently cause a metal tip assembled with a heel to be pressed firmly into contact with the top lift of the heel in position for and immediately prior to the driving of the fastening.

As illustrated herein a novel work support is 40 provided having work supporting means for moving the work into engagement with the work engaging face of a fixed presser plate or work abutment and work gripping means movable transversely of the work support to position the work 45 in engagement with an edge gage rigidly secured to the presser plate. Mechanism is provided in the form of a treadle for elevating the work support and for moving the work gripping means transversely of the support and preferably the 50 same treadle is utilized to increase the transverse pressure of the gripping means to cause the metal tip and heel to be pressed closely together after the work has been moved into engagement with the presser plate. A further feature of the invention resides in means for adjusting the initial 55

position of the work gripping means in accordance with the size of heel to be operated upon.

With the above and other objects and features in view the invention will now be described in connection with the accompanying drawings and 60 will be pointed out in the claims.

In the drawings,

Fig. 1 is a side elevation of a fastening inserting machine provided with a work support constructed in accordance with the present invention; 65

Fig. 2 is a side elevation on an enlarged scale of the work support shown in Fig. 1; and

Fig. 3 is a plan view of a heel with a metal tip attached thereto and illustrating the position of 70 the heel with respect to the fastening inserting driver and edge gage during the fastening inserting operation.

The invention is herein illustrated as applied to a fastening inserting machine of the type disclosed in the application hereinbefore referred to and reference may be made to the said application for a more complete disclosure of parts not fully described herein. The illustrated machine is provided with a main frame 10 carrying 75 at its upper end a head 12 and with a secondary column 14 carrying the work support of the present invention indicated as a whole at 16. The head 12 carries a cam shaft 18 from which the various parts of the machine are operated. 80 A driver bar 19 carrying a driver 23 is moved upwardly by means of a lifting cam (not shown) which engages a projection on the driver bar 19. A spring-pressed lever 25 fulcrumed at 27 to the head of the machine and connected by a link 29 85 with the driver bar 19 forces the driver bar 19 and driver 23 downwardly as the cam passes out from under the projection on the driver bar 19 thus driving a fastening into the work. The work 90 support is arranged to clamp the work against a presser plate 20 carried by the head 12 of the machine. The work support is moved downwardly from a pressure applying position after a fastening has been inserted into the work to allow the work to be fed by the operator and 95 upwardly into a pressure applying position to clamp the work against the presser plate 20 by suitable release mechanism, for example as disclosed in Letters Patent of the United States No. 265,227, granted September 26, 1882 on an 100 application of Louis Goddu, also driven from the cam shaft 18 by means of a cam 22. The cam 22 is connected with a horn depressing lever 24 having its fulcrum at 26 and connected 105 at 28 with the lower end of a work supporting 110

or horn post 30 carrying at its upper end the work support 16 by means of a ratchet and pawl arrangement 32 which allows the work support 16 to be depressed a predetermined amount after each fastening is inserted notwithstanding variations in the thickness of the work as more fully set forth in Letters Patent No. 265,227 referred to above.

The work support 16 is free to move vertically relatively to the horn post 30, which operates it to grip and release the work in each cycle of operation of the machine, and is provided with a sleeve 34 carrying a horn 36 for supporting the work. The sleeve 34 is slidably mounted on the upper end of the horn post 30 and is provided at its lower end with a flange 38 which when the work support is in lowermost position is seated on a flange 40 formed on the post 30. Pivoted at 44 to the lower end of the sleeve 34 is a link 42 to the lower end of which is pivotally connected a lever 46 fulcrumed at 48 to the column 14. A pull rod 50 passes through the outer end of the lever 46 and is connected at its lower end to a treadle 52 pivoted at 26 to the base of the machine. The work support 16 is elevated yieldingly when the treadle 52 is depressed by means of a coil spring 58 surrounding the rod 50 and bearing at one end against a collar 56 fast to the rod 50 and at the other end against the outer end of the lever 46. A pair of vertical links 60 are pivoted at 62 to the upper end of the column 14 and extend upwardly to a point slightly below the upper end of the horn 36. A work gripping lever 66 pivotally connected at 64 to the links 60 is provided at its upper end with a work engaging face 68 formed to engage the edge of the top lift and breast surfaces of a heel 70 mounted on the top of the horn 36. Pivotally connected to the links 60 are a pair of short links 72 carrying at their outer ends a roll 74 mounted on a fulcrum pin 76 to the outer ends of which is pivotally connected a U-shaped member 78 fast to the rod 50. The roll 74 bears against a cam surface 80 formed on the lower end of the lever 66, the arrangement being such that as the treadle 52 is depressed to raise the horn 36 the roll 74 moves in a counter-clockwise direction, as viewed in Fig. 1, through an arcuate path the extent of which is determined by the lengths of the links 72. Movement of the roll 74 in a counter-clockwise direction causes the lever 66 to swing in a clockwise direction transversely of the work support 16 until the rear edge of a metal tip, which has been assembled with the heel 70, engages a bearing surface formed on an edge gage 21 rigidly connected to the under side of the presser plate 20.

In order to adjust the initial position of the work gripping lever 66 relatively to the edge gage 21 to accommodate heels of different sizes, the links 60 are connected at their upper ends by means of a pair of links 82 which pass on either side of the horn 36 to an adjustable rod 84. At one end the rod 84 is threaded into a pin 86 pivotally mounted in a bracket 88 fast to the column 14 of the machine and at the other end the rod 84 is threaded into a block 90 mounted on trunnions between the ends of the links 82. The rod 84 is provided with a hand wheel 92 secured to the median portion thereof and has right- and left-hand threads formed thereon so that by turning the hand wheel 92 and rod 84 the links 60 and lever 66 may be moved toward or from the edge gage 21.

In order that the heel tip nails will be driven at a slight angle toward the middle of the heel the work engaging face of the presser plate is inclined at a small angle to the horizontal so that the tread surface of the heel when positioned between the presser plate and the horn tip is inclined slightly toward the front of the machine. The presser plate 20 is cut away at its front edge to facilitate locating each nail receiving hole in the metal tip properly relatively to the fastening inserting instrumentalities of the machine by the end of the projecting driver.

In operation, the treadle 52 may be depressed by the operator to bring an assembled heel and metal tip approximately into engagement with the presser plate 20 and edge gage 21. A nail receiving hole in the metal tip may then be located properly relatively to the fastening inserting instrumentalities of the machine by the end of the projecting driver in the manner described in application Serial No. 473,150 referred to above. A slight further depression of the treadle 52 will cause the heel and metal tip to be pressed simultaneously upwardly into engagement with the presser plate 20 and rearwardly into engagement with the gage 21 with the end of the fastening inserting driver threaded into a nail receiving hole formed in the metal tip. Further depression of the treadle 52 will cause the work gripping lever 66 to push the heel transversely of the horn 36 firmly against the metal tip so that the metal tip will be held closely in contact with the cut-out portion of the top lift of the heel during the fastening inserting operation after which the clutch operating treadle of the machine may be tripped in the usual manner and a fastening inserted into the work.

Having thus described my invention what I claim as new and desire to secure by Letters Patent of the United States is:

1. A work support for a fastening inserting machine provided with a fixed presser plate and a gage, said work support comprising a work supporting member in opposed relation to said presser plate and a work gripping member in opposed relation to said gage, said members being mounted for movement toward the presser plate and gage to clamp a work piece therebetween.

2. A work support for a fastening inserting machine provided with a presser plate and a gage, said work support comprising a supporting member movable toward said presser plate to clamp an assembled heel and metal tip therebetween, and a work gripping member mounted for movement simultaneously with the first-mentioned member transversely of the supporting member to press the work against the gage to cause the metal tip to be pressed closely into engagement with the heel prior to the insertion of a fastening.

3. A work support for a fastening inserting machine provided with a fixed presser plate and a gage, said work support comprising a supporting member arranged yieldingly to clamp a work piece against the presser plate, and a cooperating work gripping member mounted for movement to clamp the work against the gage, said members being constructed and arranged for movement simultaneously toward clamping position.

4. A fastening inserting machine having a fixed abutment, a work support comprising a supporting member in opposed relation to said fixed abutment, means for moving the supporting member toward the abutment to clamp a piece of work therebetween, and means for moving the work piece transversely of the work support after

- clamping pressure has been applied to the work.
5. A fastening inserting machine having an abutment, a gage, a work support comprising a work supporting member in opposed relation to said abutment, a work gripping member in opposed relation to said gage, means for moving said members toward the abutment and gage to clamp a work piece therebetween, and means for adjusting the initial position of the gripping member to accommodate work pieces of different sizes. 80
6. A fastening inserting machine having a presser plate, a gage, and a work support comprising a plurality of work engaging members constructed and arranged simultaneously to press an assembled heel and metal tip upwardly into engagement with the presser plate and rearwardly into engagement with the gage thereby to cause the metal tip to be pressed closely into engagement with the heel prior to the fastening inserting operation. 85
7. A fastening inserting machine having a presser plate, a gage, a work support having a plurality of work engaging members constructed and arranged simultaneously to press an assembled heel and metal tip upwardly into engagement with the presser plate and rearwardly into engagement with the gage, automatic means for applying additional upward pressure to the work, and means for inserting a fastening into the work. 90
8. A fastening inserting machine having a presser plate, a gage, a work support having a plurality of work engaging members constructed and arranged simultaneously to press an assembled heel and metal tip upwardly into engagement with the presser plate and rearwardly into engagement with the gage, one of said members being mounted for yielding movement while additional pressure is applied to the heel by the other member to force the heel and metal tip firmly together prior to the insertion of a fastening therein. 100
9. A fastening inserting machine having a presser plate, a gage, and a work support comprising a plurality of work engaging members constructed and arranged simultaneously to press an assembled heel and metal tip upwardly into engagement with the presser plate and rearwardly into engagement with the gage, and means for adjusting the initial position of one of said members to accommodate heels of different sizes. 105
10. A fastening inserting machine having, in combination, a presser plate, a gage, a horn post, a horn carried thereby and mounted for vertical movement relatively thereto, means for moving the horn relatively to the horn post to clamp a work piece against the presser plate, and a work gripping lever operatively connected to said last-named means and arranged to move the work into engagement with the gage as upward clamping pressure is applied to the work and for thereafter applying pressure to the work transversely of the horn prior to the fastening inserting operation. 110
11. A fastening inserting machine, having, in combination, an abutment, a work support comprising a member for supporting an assembled heel in opposed relation to said abutment, treadle operated means for moving said supporting member toward the abutment to clamp the assembled heel therebetween, and means also controlled by said treadle for moving the heel transversely of the work support after clamping pressure has been applied to the heel. 115
12. A fastening inserting machine having a presser plate, a gage, a horn post, a horn carried thereby and mounted for vertical movement relatively thereto, means for moving the horn relatively to the horn post to clamp an assembled heel against the presser plate, and a heel-gripping member for applying pressure to the heel transversely of the horn to move the heel into engagement with the gage. 120
13. A fastening inserting machine having a presser plate, a gage, a horn post, a horn carried thereby and mounted for vertical movement relatively thereto, means for moving the horn relatively to the horn post to clamp a work piece against the presser plate, and a work gripping lever operatively connected to said last-named means and arranged to move the work into engagement with the gage as clamping pressure is applied to the work. 125
14. A fastening inserting machine having, in combination, a presser plate, a gage, a horn post support, a horn post, a work supporting horn carried by said horn post and mounted for vertical movement relatively thereto, a pivoted work gripping lever mounted on said horn post support, and means for elevating said horn relatively to its support and for swinging said gripping lever about its fulcrum whereby a work piece carried by said horn may be moved upwardly into engagement with the presser plate and rearwardly into engagement with the gage prior to a fastening inserting operation. 130
15. A fastening inserting machine having, in combination, a presser plate, a gage, a horn post support, a horn post, a work supporting horn carried by said horn post and mounted for vertical movement relative thereto, an adjustable work gripping lever pivotally mounted on said horn post support, and operator controlled means for simultaneously swinging said work gripping lever about its fulcrum and for elevating said horn relatively to its support whereby a work piece may be moved upwardly into engagement with the presser plate and rearwardly into engagement with the gage prior to a fastening inserting operation. 135
16. A fastening inserting machine having, in combination, a presser plate, a gage, a horn post, a horn carried thereby and mounted for vertical movement relatively thereto, means for moving the horn relatively to the horn post to clamp a work piece against the presser plate, an adjustable work gripping lever operatively connected to said last-named means and arranged to move the work into engagement with the gage as upward clamping pressure is applied to the work, and means for adjusting the initial position of the gripping lever relatively to the gage. 140
17. A fastening inserting machine having, in combination, a presser plate, a gage, a horn post, a horn carried thereby and mounted for vertical movement relatively thereto, treadle operated means for moving the horn relatively to the horn post to clamp a work piece against the presser plate, an adjustable work gripping lever operatively connected to said last-named means and arranged to move the work into engagement with the gage as upward clamping pressure is applied to the work and for thereafter applying pressure to the work transversely of the horn, automatic means for applying additional upward pressure to the work, and means for inserting a fastening into the work. 145
18. A fastening inserting machine having, in combination, a presser plate, a gage, a horn post support, a horn post, a work supporting horn car- 150

ried by said horn post and mounted for vertical movement relatively thereto, treadle operated means for moving said horn post upwardly yieldingly to clamp a work piece against the presser plate, a pair of links carried by said horn post support, a work gripping lever pivotally connected to said links and having a work engaging face formed and arranged to engage the top and side surfaces of a work piece supported by said horn, and means also controlled by said treadle for swinging said work gripping lever about its fulcrum to move the work supported by the horn into engagement with the gage.

19. A fastening inserting machine having, in combination, a presser plate, a gage, a horn-post support, a horn post, a work-supporting horn carried by said horn post and mounted for vertical movement relatively thereto, a pair of links carried by said horn-post support, a work-gripping lever pivotally connected to said links and having a work-engaging face formed and ar-

ranged to engage the top and side surfaces of a work piece supported by said horn, a second pair of links pivotally connected to said pair of links, a roll carried by said second pair of links and arranged to engage a cam surface formed on said work-gripping lever below its pivotal point, and a treadle positively connected to said second pair of links and yieldingly connected to said work-supporting horn whereby depression of said treadle is at first effective to cause said work-supporting horn to move upwardly yieldingly to clamp a work piece against the presser plate and to swing said work-gripping lever about its fulcrum to move the work supported by the horn into engagement with the gage.
